DESIGN FOR A CIGAR LIGHTER.

Application filed April 12, 1928. Serial No. 26,291. Term of patent 3½ years.

To all whom it may concern:

Be it known that we, CHARLES E. BEARDSLEY and EDWARD P. WALLACE, citizens of the United States, residing at Waterbury, county of New Haven, and State of Connecticut, have invented a new, original, and ornamental Design for Cigar Lighters, of which the following is a specification, reference being had to the accompanying drawing, forming part thereof.

Fig. 1 is a front view of the cigar lighter.
Fig. 2 is a top view of the same.

We claim:

The ornamental design for a cigar lighter as shown.

In testimony whereof, we have affixed our signatures to this specification.

CHARLES E. BEARDSLEY.
EDWARD P. WALLACE.
